CIRCULATING OIL SYSTEM FOR PRESSES

Philo H. Danly, Hinsdale, George I. Danly, Elmhurst, and Vasil Georgeff, Chicago, Ill., assignors to Danly Machine Specialties, Inc., Chicago, Ill., a corporation of Illinois

Application November 3, 1947, Serial No. 783,746

12 Claims. (Cl. 184—6)

1

Our invention relates to a circulating oil system for presses, and more particularly to an improved lubricating system for power presses.

Power presses are employed for forming or shaping metal and frequently form part of production lines. They are expensive pieces of equipment and it is desirable to lengthen their life by proper lubrication. Furthermore, if a breakdown occurs in a power press forming part of a production line, the interruption of the entire line represents a considerable economic loss.

The power presses of the prior art have been provided with individual lubricating means for various parts to be lubricated. The gears of the power train usually run in a bath of oil in which the rotation of the gears themselves is relied upon to distribute the oil to the gear contact point. If the press has been standing idle for a considerable period of time, it frequently happens that the contacting gears are substantially dry or insufficiently lubricated, with the result that metal-to-metal contact is permitted, resulting in excessive wear, introducing lost motion which adversely affects the accuracy of the work and reduces the life of the press. Separate lubricating means have been provided for the ram adjustment by which the stroke of the ram to accommodate differing dies and work of different thicknesses is varied, and for the bearings of different shafts. These lubricating means are frequently neglected and inadvertently allowed to run dry with the result that inadequate lubrication frequently exists in the power presses of the prior art.

One object of our invention is to provide a common lubricating system for all moving parts.

Another object of our invention is to provide a lubricating system for power presses in which the moving parts are positively and continuously supplied with a lubricating medium.

Another object of our invention is to provide a continuous circulating system in which the lubricant from a central source is circulated to all moving parts, returned to the source, filtered and recirculated.

Another object of our invention is to provide a continuous lubricating system in which danger of spraying of oil over the work or the operator of the press is avoided.

Another and further object of our invention will appear from the following description.

Fig. 1 is a diagrammatic perspective view showing a portion of our lubricating system.

Fig. 2 is a diagrammatic view showing an elevation of the improved lubricating system shown in Fig. 1.

Fig. 3 is a plan view of the system shown in Fig. 1.

Fig. 4 is a fragmentary sectional elevation of a part of a power press showing another portion of our improved system.

Fig. 5 is a fragmentary elevation with parts in

2

section of the upper portion of a sliding joint used in our improved system.

Fig. 6 is a view similar to Fig. 4 showing the lower portion of the sliding joint.

Fig. 7 is an end view of the oil filter assembly used in our invention.

Fig. 8 is a sectional view taken on the line 8—8 of Fig. 7.

In general, our invention contemplates the provision of an oil sump on the ram of the press which is driven to reciprocate by the pitmans which are actuated by the eccentrics of the press. An oil distribution system is provided for lubricating the gear trains, the bearing shafts for the gears, the eccentric gear bearings, the pitman and the ram adjustment assembly. Oil is continuously supplied to the oil distribution system by means of a pump and allowed to flow downwardly by gravity from the crown of the press to the sump, whence it is filtered and recirculated. Since the oil reservoir is carried by a reciprocating part and a portion of the oil distribution system is mounted on a stationary part of the press, a sliding oil-tight connection is provided to furnish a conduit for the oil in a manner to preclude the sliding connection from acting as a pump per se so that oil under a predetermined pressure may be continuously distributed to the working parts of the press.

More particularly, referring now to Fig. 4, the ram of the press is indicated generally by the reference numeral 10 and is reciprocated through a pair of pitmans 12 and 14 which are pivotally connected to pins 16 which are adjustably carried by members 18 of the ram adjustment assembly lodged in housings 20 which form part of the ram. Adjustment of the ram stroke is made by means of screws 22 through adjusting members 24 which are rotated in unison by a motor 26 driving shafts 28 and 30. An oil reservoir or sump 32 is formed by a sheet metal housing 34. A motor 36 drives a pump 38 through shaft 40. A filter assembly, indicated generally by the reference numeral 42, is provided for filtering the oil from the reservoir 32. The pump 38 is provided with an inlet pipe 44, connected to the filter assembly, to which oil is drawn through pipe 46 from the oil sump. The pump discharges oil through pipe 48 which is adapted to reciprocate with the press ram 10.

50 The pipe 48 passes through a stationary housing 50 of the sliding or "trombone" joint of the oil distribution system.

Referring now to Fig. 1, a discharge pipe 52 communicates with the housing 50. Oil flows from pipe 52 through branch pipe 54 to a manifold 56. An outlet pipe 58 supplies oil to the forward bearing 60 of the left hand gear train shaft 62. An outlet pipe 64 supplies oil to the forward bearing 66 of the right hand gear train shaft 68. The gear train shaft 68 carries a gear 70 which meshes with a gear 72. The right hand gear train shaft 68 carries a pinion 74

which meshes with right hand eccentric gear 76. The gear train shaft 62 carries a pinion 78 which meshes with a left hand eccentric gear 80. A second distribution pipe 82 communicates with the manifold 56 and supplies oil to the manifold 84. An outlet pipe 86 supplies oil to the rear bearing 88 of the right hand gear train shaft 68. An outlet pipe 90 supplies oil from the manifold 84 to the rear bearing 92 for the left hand gear train shaft 62. A branch conduit 94 supplies oil to the rear bearing 96 of the flywheel shaft 98. Oil from the housing 52 passes through pipe 100, through pipe 102 to the forward bearing 104 of the flywheel shaft 98. The flywheel shaft carries a pinion 106 which meshes with gear 72 so that both gears 72 and 70 are driven from pinion 106. An outlet pipe 108, communicating with the pipe 100, provides oil to the gears 70, 72 and hence the pinion 106 meshing therewith. A branch pipe 110, communicating with manifold 56, provides oil through outlet pipe 112 to the right hand pitman. The branch pipe 110 provides oil through outlet pipe 114 to the right hand eccentric gear bearing. Similarly, a distribution pipe 116 communicates with the manifold 56 and provides oil through outlet pipe 118 to the left hand pitman 14. An outlet pipe 120 provides oil to the left hand eccentric gear bearing. A pipe 122 leads to a pressure gauge to indicate the oil pressure within the system.

A branch pipe 124, leading from the second distribution pipe 82, furnishes oil to the eccentric gear 80 from which it is distributed over the pinion 78. Similarly, a branch pipe 126 furnishes oil to the eccentric gear 76 from which oil is distributed over the pinion 74. The crown of the press housing the gears is enclosed so that oil, after lubricating the parts of the press falls downwardly by gravity. The oil from the left hand parts is deflected by deflection plate 128. The oil from the right hand part is deflected by a deflection plate 130. The oil flows downwardly through an opening 132 through which the pitman 12 passes. Similarly, the oil from the left hand side of the press flows through opening 134 through which the pitman passes. A collecting pan 136 is placed below the opening 132 and a collecting pan 138 is placed below the opening 134. The pan 136 is formed with an opening 140 through which oil may flow downwardly to lubricate the bearing between the lower end of the pitman and the pin 16. Oil may also flow downwardly to lubricate the adjusting member 24 and its friction surfaces, finally overflowing through pipe 142 back to the sump 32. In a similar manner, oil flows from the pan 138 to lubricate the parts within the left hand housing 20 for the ram adjustment mechanism. This oil flows through pipe 144 back to the sump. Excess oil from collecting pan 136 flows out of outlet 146 and excess oil from pan 138 flows out of outlet pipe 148. This oil is collected in the sump 32 for recirculation.

The filter assembly, which is indicated generally by the reference number 42, is shown in detail in Figs. 7 and 8. It comprises a housing 150, having an inlet fitting 152, provided with a seat 154 against which a valve 156 is adapted to seal the inlet opening 158. The suction pipe 46 is threadedly secured to the fitting 152. A filter cartridge 160 is removably secured within the housing 150. Oil which passes through the filter 160 enters the manifold 162 with which the suction pipe 46 communicates. After the filter has been in use for a time, it may become clogged. When this occurs, the handle 164 is rotated to

alignment with slots 166, permitting the spring 168 to seat the valve 156 on the valve seat 154, thus closing off the oil delivery pipe 46. Screws 170 are then unloosened and a filter 160 is removed through handle 172. The filter cartridge 160 is removed and replaced by a new filter assembly. When the cover plate 174 has been removed, the interior of the housing 150 may be cleaned of any sediment.

Referring now to Figs. 5 and 6, the oil pump 38 discharges through coupling 39 to the pipe 48 through a T connection 49. The lower end of the T is firmly secured to a base 51. The pipe 48 projects upwardly through a flanged member 53 which is firmly secured to a stationary structural part of the press 55 by means of bolts 57. The housing 50 is threadedly secured to the upper end of the flanged member 53. The lower end of the flanged member is closed by a threaded plug 59 provided with sealing packing rings 61 and 63.

In Fig. 6, the position of parts is shown when the ram is at its lowermost position and about to begin its upward stroke. The pipe 48 is provided with holes 65, providing communication between the pipe 48 and the housing 50.

Referring now to Fig. 5, the upper end of the pipe 48 is closed with a cap 67. The upper end of housing 50 is provided with a T 69 threadedly secured thereto. The upper end of the T is closed with a plug 71, provided with an opening through which the pipe 48 passes and with sealing packing rings 73 and 75. The pipe 52 communicates with the T 69 by means of an elbow 77.

In use, before the press is started, the motor 36 is energized, thus driving pump 38 and starting the oil circulation upwardly through pipe 48, housing 50 and the distribution system described above. The flywheel shaft bearings 96 and 104

are supplied with lubricant. This is true, too, of the gear shaft bearings 88 and 66 and 92 and 60. The gears themselves are supplied with a stream of lubricant. The eccentric shaft bearing and the pitman bearings are likewise lubricated.

Oil flows downwardly by gravity and lubricates the ram adjusting mechanism. When the press is started, the ram will reciprocate, permitting the pipe 48 to slide in the housing 50. It will be observed that a continuous oil-tight packing is provided for the lubricating oil even though the pump and sump are carried upwardly and downwardly by the ram and the distributing system is on the stationary framework of the press. The oil is filtered and continuously circulated so that all of the friction surfaces are amply and plentifully supplied with a lubricating medium.

It will be seen that we have accomplished the objects of our invention. We have provided a common lubricating system for all the moving parts of a power press, by which these parts are positively and continuously supplied with lubricating oil. We have provided a continuous circulating system in which lubricating oil from the central source is circulated to all moving parts, returned to the source, filtered and recirculated. There is no danger of spraying the lubricating oil over the work or over the operator of the press, since the crown of the press adjacent the gears is completely enclosed. We have eliminated the plurality of the lubricating devices which, in the prior art, are subject to neglect and inattention, with the result that the press parts are always adequately lubricated.

We have shown our lubricating system applied to a press employing twin pitmans, by way of

Illustration and not by way of limitation. It is to be understood that our invention may be employed with other types of presses.

We have found that a pressure from twenty to twenty-five pounds per square inch will provide an ample flow of lubricant under the most arduous working conditions. Any suitable pressure may be employed. The oil pressure within the system is indicated by the pressure gauge 99 shown in Fig. 3. A variation of pressure may easily be achieved by regulating the speed at which the motor 36 which drives the pump is run. The oil pressure gauge, being readily visible to the operator, serves as a constant safety means to insure adequate lubrication of all of the press parts. Since the motor 36 will pump oil through the circulating system when the press is at rest, all the parts are adequately lubricated independently of whether or not the press is running.

It will be understood that certain features and sub-combinations are of utility and may be employed without reference to other features and sub-combinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, what we claim is:

1. A power press, including in combination a frame, a ram adapted to reciprocate in said frame, drive mechanism carried by said frame adjacent the upper portion thereof, an oil reservoir carried by said ram, means for supplying oil from said reservoir to said drive mechanism and means for redirecting oil from the drive mechanism to the oil reservoir for recirculation.

2. A power press including in combination a frame having a crown, a ram adapted to reciprocate in said frame, drive mechanism positioned in said crown, said drive mechanism including a drive shaft, bearings for said drive shaft, an oil reservoir carried by said ram, means for supplying oil from said reservoir to said drive shaft bearings and means for redirecting oil from the drive shaft bearings to the oil reservoir for recirculation.

3. A power press including in combination a frame having a crown, a ram adapted to reciprocate in said frame, a drive mechanism positioned in said crown, said drive mechanism including a drive shaft having a drive pinion and bearings, a power shaft having a gear meshing with said pinion and having bearings, an oil reservoir mounted on said ram, means for supplying oil from said reservoir to said bearings and means for redirecting oil from said bearings to said reservoir for recirculation.

4. A power press including in combination a frame having a crown, a ram adapted to reciprocate in said frame, drive mechanism positioned in said crown for reciprocating said ram, said drive mechanism including a pitman and an eccentric, an oil reservoir carried by said ram, means for supplying oil from said oil reservoir to said pitman and eccentric and means for redirecting oil from said pitman and eccentric to said reservoir for recirculation.

5. A power press including in combination a

frame, a ram adapted to reciprocate in said frame, drive mechanism carried by said frame adjacent the upper portion thereof for reciprocating said ram, an oil reservoir carried by said ram, an oil pump carried by said ram, an oil conduit for supplying oil to said drive mechanism, said conduit including a flexible joint.

6. A power press as in claim 5 wherein said flexible joint comprises a stationary housing, a reciprocating pipe positioned in said housing and extending therethrough, means for packing the upper and lower portions of said housing around said movable pipe and means providing communication between said pipe and said housing within the housing.

7. A power press including in combination a frame having a crown, a ram carried by said frame for reciprocation therein, drive mechanism positioned in said crown for reciprocating said ram, an oil reservoir carried by said ram, an oil pump having an inlet pipe communicating with said reservoir, a conduit for supplying oil discharged by said pump to said drive mechanism in said crown, said conduit including a flexible joint and baffles carried by said frame for redirecting oil supplied to said drive mechanism to said reservoir for recirculation.

8. A power press as in claim 7 including in combination a baffle carried by said ram, ram-adjusting means for regulating the throw of said ram, said ram baffle being positioned to direct oil flowing downwardly from said drive mechanism to lubricate said ram-adjusting means.

9. A power press as in claim 7 including an oil filter interposed between said reservoir and said pump.

10. A power press as in claim 7 in which said flexible joint includes a stationary housing, a reciprocating pipe positioned in said housing and extending therethrough, means for packing said reciprocating pipe adjacent the upper and lower ends of the housing and means providing communication between the interior of said pipe and said housing within said housing.

11. A power press as in claim 7 in which the oil conduit includes an oil-distributing manifold positioned in said crown, said manifold having branch pipes for lubricating various portions of said drive mechanism.

12. A power press as in claim 7 in which the oil conduit includes an oil-distributing manifold positioned in said crown, said manifold having branch pipes for lubricating various portions of said drive mechanism, a pressure gauge and a branch pipe providing communication between said manifold and said pressure gauge.
